CLAIM

The ornamental design for an audio remote controller, as shown and described.

DESCRIPTION

FIG. 1 is a front view of an audio remote controller showing our new design;

FIG. 2 is a left side view thereof;

FIG. 3 is a right side view thereof;

FIG. 4 is a top plan view thereof;

FIG. 5 is a bottom plan view thereof;

FIG. 6 is a rear view thereof;

FIG. 7 is a cross sectional view taken along line 7—7 in FIG.

1, wherein detail of inner structures is omitted; and,

FIG. 8 is a cross sectional view taken along line 8—8 in FIG. 1, wherein detail of inner structures is omitted.
